H. E. WINANS

FIREARM

Filed Dec. 5, 1923

FIG. I

FIG. II

FIG. IV

INVENTOR
Henry E. Winans.
Cook & M. Cauley
BY
ATTORNEYS

UNITED STATES PATENT OFFICE.

HENRY E. WINANS, OF ALTON, ILLINOIS.

FIREARM.

Application filed December 5, 1923. Serial No. 678,627.

To all whom it may concern:

Be it known that I, HENRY E. WINANS, a citizen of the United States of America, a resident of Alton, in the county of Madison and State of Illinois, have invented certain new and useful Improvements in Firearms, of which the following is a full, clear, and exact description, reference being had to the accompanying drawings, forming a part of this specification.

This invention relates generally to improvements in firearms, and particularly to a firearm of the type which is aimed by sighting along the barrel at the object to be fired upon.

Most rifles, shotguns and similar firearms are aimed by sighting along the upper faces of the barrels thereof, and prior to this invention much inconvenience has been caused by heat waves which arise from said barrels. This is particularly true in connection with firearms which are fired a great number of times without the lapse of a sufficient interval of time to permit the barrels of the firearms to cool, such as shotguns which are used in the sport of trap shooting. The passage of heat waves from the barrel of a firearm causes a mist to form along the path of sight, which mist interferes with the vision of the person using the firearm and prevents accurate aiming of said firearm.

Prior to this invention firearms have been provided with ribs of various shapes and arrangements which were intended to eliminate the difficulty mentioned above, but none of these ribs functioned in an entirely successful manner. The present invention contemplates the use of a rib which is formed of a material which is impervious to heat, said rib acting to insulate the heated barrel of the firearm from the space immediately above the rib, whereby the troublesome heat waves mentioned are eliminated from the path of sight and a clear vision of the object aimed at is permitted.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which

come within the scope of the claims hereunto appended.

Fig. I is a perspective view of a firearm constructed in accordance with my invention.

Fig. II is an enlarged fragmentary side elevation of a portion of a firearm made in accordance with my invention, said firearm being broken away in spots to show the manner of applying my improved rib thereto.

Fig. III is an enlarged cross section through the barrel of a firearm shown in Fig. I.

Fig. IV is a fragmentary view on a reduced scale showing a firearm provided with an auxiliary rib having an inclined top face.

In the drawing A designates a firearm of the type which is aimed by sighting along the barrel thereof, said firearm having the usual stock B, breech C and barrel D. The firearm illustrated in the drawing is of the repeating type, but as the mechanism which permits repeated firing forms no part of the present invention it will not be described.

The barrel of the firearm shown in the drawing is provided with an integral rib 1 which extends upwardly from said barrel and is arranged the full length thereof. As will be seen by referring to Figs. I and II of the drawing, that portion of the wall of the barrel at the rib 1 is substantially thicker than the balance of the wall of the barrel, and formed in this thickened portion of the barrel is a longitudinally extending dovetail groove 2. The dovetail groove 2 extends from a point slightly removed inwardly from the end of the rib to the extreme inner end of said rib as shown in Fig. III. By terminating the dovetail groove short of the outer end of the barrel D an upstanding wall 3 is produced which is intended for a purpose to be hereinafter set forth.

4 designates an auxiliary rib which is in cross section the approximate shape of a letter T, the downwardly extending portion 4' of said auxiliary rib being of such size and shape as to be capable of being introduced into the dovetail groove 2 just described, and the laterally extending portions 5 of said auxiliary rib being adapted to rest on the top face of the rib 1 of the firearm on either side of the groove 2 when said rib is in place in said groove. The auxiliary rib 4 is also provided with a portion 6 which

extends outwardly from the front end of said rib, said portion when the auxiliary rib is in place being located on the top face of the upstanding wall 3, as shown in Fig. III.

5 The auxiliary rib 4 is located in place on the barrel D of a firearm when said barrel is detached from the stock of said firearm, the portion 4' of said auxiliary rib being introduced into the dovetail groove 2 at the 10 rearmost end of said groove and said auxiliary rib being moved longitudinally of said groove until the abutment face 4^a of said rib contacts with the abutment face D^a of said barrel. The auxiliary rib 4 is of such 15 length that when said rib is in its proper position and the barrel of the firearm is attached to the stock thereof, the rearmost face of said rib will contact with the front face C' of the breech of the firearm whereby 20 said rib is prevented from being accidentally moved rearwardly, and because the contacting abutment faces 4^a and D^a prevent said rib from moving forwardly and the inclined walls of the dovetail groove 2 prevent 25 said rib from moving upwardly, it is apparent that said auxiliary rib is securely held in its proper position on the barrel of the firearm.

30 The auxiliary rib 4 is made from a material which is impervious to heat, such, for instance, as bakelite, and regardless of the intensity of the heat of the barrel no heat waves will pass upwardly into the path of sight of the person aiming the firearm, said auxiliary rib acting as an insulator and 35 keeping said path of sight absolutely free from the troublesome mist already referred to.

40 As the temperature of the barrel of a firearm changes there is a slight expansion and contraction of the metal of said barrel. In the use of a firearm constructed in accordance with my invention this slight movement may take place without affecting the auxiliary rib, as the inclined wall of the groove 2 may move relative to the inclined faces of the portion 4' of the auxiliary rib 4. In this connection it will be necessary to make the auxiliary rib of slightly less 45 length than the groove 2 so that the barrel of the firearm may contact longitudinally without crushing said rib.

50 In Fig. IV I have illustrated the barrel portion of a firearm which is provided with a rib 1^a, said firearm being provided with a dovetail groove 2^a similar to the dovetail groove 2 of the firearm already described. The firearm illustrated in Fig. IV is provided with an auxiliary rib 4^a which has a 55 portion so shaped as to be capable of being inserted into the dovetail groove 2^a of the firearm. The auxiliary rib 4^a is provided with an inclined top face; in other words, 60 said top face of said rib is a greater distance from the axis of the barrel at the

outer end of said barrel than it is at the end of the barrel adjacent to the breech C^a of the firearm. By this arrangement a firearm may be provided with an auxiliary rib which will cause the firearm to be aimed below the objects to be fired upon, due to the fact that the person aiming the firearm sights along the top face of the auxiliary rib and if this auxiliary rib is higher at one end, as illustrated in Fig. IV, it will be necessary to lower the outer end of the barrel of the firearm to sight the object along said top face of said auxiliary rib.

I claim:

1. A firearm having a barrel, and a rib extending longitudinally of said barrel, said rib being formed of a material impervious to heat whereby the space immediately above said rib is kept free from heat waves arising from said barrel.

2. A firearm having a barrel, and a rib extending longitudinally of said barrel, said rib being formed of a material impervious to heat whereby the space immediately above said rib is kept free from heat waves arising from said barrel, and said firearm barrel being capable of slight movement relative to said rib.

3. A firearm having a barrel provided with a longitudinally extending groove, and a rib seated in said groove, said rib being formed of a material impervious to heat whereby the space immediately above said rib is kept free from heat waves arising from said barrel.

4. A firearm having a barrel provided with a longitudinally extending dovetail groove, and a rib seated in said groove, said rib being formed of a material impervious to heat whereby the space immediately above said rib is kept free from heat waves arising from said barrel.

5. A firearm having a barrel provided with a longitudinally extending dovetail groove, and a rib approximately T-shaped in cross section a portion of which is adapted to be introduced into said groove, said rib being formed of a material impervious to heat whereby the space immediately above said rib is free from heat waves arising from said barrel.

6. A firearm having a barrel provided with a longitudinally extending groove in its upper face, a rib seated in said groove, means whereby said rib is prevented from moving upwardly in said groove, and means whereby said rib is prevented from moving longitudinally of said groove, said rib being formed of a material impervious to heat whereby the space immediately above said rib is kept free from heat waves arising from said barrel.

7. A firearm having a barrel provided with a longitudinally extending dovetail groove in its upper face, a rib a portion of

which is seated in said groove, means comprising abutment faces at the opposite ends of said barrel whereby said rib is prevented from moving longitudinally of said groove, 5 said rib being formed of a material impervious to heat whereby the space immediately above said rib is kept free from heat waves arising from said barrel and said barrel being capable of slight movement relative 10 to said rib.

8. A firearm having a barrel, and a rib extending longitudinally of said barrel, said

rib being provided with an inclined top face along which the object being fired upon is sighted. 15

9. A firearm having a barrel, and a rib extending longitudinally of said rib, said rib being formed of a material impervious to heat and said rib being provided with an inclined top face along which the object 20 being fired upon is sighted.

In testimony that I claim the foregoing I hereunto affix my signature.

HENRY E. WINANS.
